ELECTRIC HOIST

Cornelius Brongersma, Muskegon Heights, Mich.,
assignor to Manning, Maxwell & Moore, Inc.,
Muskegon, Mich., a corporation of New Jersey

Application September 6, 1938, Serial No. 228,513

10 Claims. (Cl. 254—168)

The invention relates to electric hoists, and more particularly to hoists embodying a reversible electric driving motor.

In the copending application of Preston Whitcomb, Serial No. 228,509, filed September 6, 1938, an electric hoist is disclosed embodying a single phase alternating current motor of the starting winding type, and in which a control and brake arrangement is provided adapting such a motor for reversing operation in a hoist. The present invention is in general an improvement upon the construction disclosed in said Whitcomb et al. application.

One object of the present invention is to provide in an electric hoist an improved form of controller actuating mechanism by virtue of which a relatively long period of dwell is obtained when shifting the hoist controller from lowering to hoisting position or vice versa. During this period of dwell, the brake on the hoist is automatically set so that it slows down the driving motor to such a point that the speed responsive switch, which controls the motor starting winding, is actuated thereby cutting the starting winding into circuit. This action is particularly important in view of the fact that it is an inherent characteristic of single phase alternating current starting winding motors that they can only be reversed when the starting winding is in circuit.

Another object of the invention is to provide in an electric hoist an improved form of actuating mechanism which not only serves to insure a relatively long period of dwell when shifting the hoist controller from lowering to hoisting position, or vice versa, but which also cooperates with the hoist line so as to act as an automatic limit control for stopping the hoist motor when the hoist line reaches either of its extremities of movement.

The invention also resides in various structural improvements and combinations of elements in the controller actuating mechanism by means of which a positive snap action of the controller is obtained.

Further objects and advantages of the invention will become apparent as the following description proceeds taken in connection with the accompanying drawings, in which:

Figure 1 is a general perspective view of an electric hoist embodying the invention.

Fig. 2 is an enlarged transverse sectional view of the hoist shown in Fig. 1, illustrating particularly the hoist control and brake mechanism with the associated parts shown in dot-dash lines.

Fig. 3 is a wiring diagram of the motor control circuits for the hoist of Fig. 1.

Fig. 4 is an enlarged vertical longitudinal sectional view of the hoist of Fig. 1, illustrating particularly the controller and brake actuating mechanism with the associated general parts of the hoist indicated in dot-dash lines.

The particular hoist to which the invention is applied herein (Fig. 1) embodies as its principal elements a reversible electric driving motor 10, a revolvable hoisting member in the form of a chain pinion 11 (Fig. 4) and which is connected in driven relation with the motor through a speed reduction gearing contained within a gear case 12. The hoisting pinion 11 is journaled within a housing 13 (Fig. 1) formed as an integral extension on the inner face of the gear case 12 directly below the motor 10, while the motor itself is bolted to an integral cylindrical extension 14 on the gear case. The hoist unit is supported by a suitable hook 15, which is attached to the upper side of the gear case extension 14, and disposed substantially in vertical alignment with the hoisting pinion 11. A hoist line, shown in the form of a roller-type chain 11a, is reeved over the pinion 11 and has one end secured to the gear case extension 14 by a suitable tension spring 11b. A load hook 11c is secured to the other end of the chain. A brake mechanism, designated generally by the numeral 16, is provided for holding the motor 10 and chain pinion 11 against rotation whenever the motor is stopped. This brake mechanism may, for the sake of compactness, be housed within the cylindrical gear case extension 14 (Fig. 4). It should be understood that the general arrangement of the hoist parts described above and their particular form constitutes no part of the present invention. The particular arrangement of parts described above is in fact disclosed and claimed in the copending application of Christopher H. Schramm, Serial No. 228,511, filed September 6, 1938.

The improved form of controller actuator mechanism herein contemplated is particularly adapted for use in hoists embodying an electric driving motor of the single phase alternating current starting winding type. The motor 10 has been shown (Fig. 3) as being of this general type and is of a form commonly designated as a "split phase" motor. It embodies a main winding 17 and an auxiliary starting winding 18. In order to make the motor as low in cost as possible, the starting winding 18 is designed to have a low current carrying capacity, and accordingly must be cut out of circuit after the motor has

started in order to avoid burning it out under sustained load. To this end, a speed responsive switch 19 is connected in series with the starting winding 18. This switch may be of the conventional centrifugal type ordinarily supplied in such motors, and in general is arranged to open, and thereby deenergize, the starting winding 18 as soon as the motor 10 accelerates to a speed of predetermined value. During stoppage of the motor, the switch 19 will again close during the deceleration period, although sometimes at a somewhat lower speed than that at which it opens due to the inherent sluggishness of such switches.

It is a characteristic of starting winding motors like that described above that they can only be reversed when the starting winding is in circuit. In other words, if the motor 10 is operating at normal speed in one direction, and hence with the starting winding 18 deenergized, a mere reversal in the instantaneous polarity of the voltage applied to the main winding 17 will not serve to reverse the motor but will, on the other hand, serve to continue it in rotation in the same direction. This action is to be distinguished from that obtained in more expensive types of reversible motors in which a simple reversal of the instantaneous polarity of the voltage applied to the motor will cause it to reverse. In common electrical engineering parlance, the motor 10 illustrated herein cannot be "plugged." Consequently, in order that the motor 10 may be reversed so as to change from hoisting to lowering or vice versa, it is necessary that the reversal operation include an energization of the starting winding 18. In general, the improved actuating mechanism herein disclosed is of such character that there will be a relatively long period of dwell between the time that the motor connections are set up for one direction of rotation the instant at which they are reversely connected. During this period of dwell, the motor is deenergized and the brake mechanism 16 applied so that the motor is slowed down to a point at which the speed responsive switch 19 recloses, thereby cutting the starting winding 18 back into circuit. By providing a relatively long period of dwell, as distinguished from an almost instantaneous change-over, a sufficient slowing down of the motor is insured to accomplish the necessary closure of the speed responsive switch 19.

In the illustrative construction, a reversing controller 20 (Fig. 4) is provided which is of conventional construction and is secured to the lower side of the motor 10 by a bracket 21. This controller includes a rock shaft 22 carrying a cross arm 23 on its outer end. When the rock shaft 22 is in the position illustrated in Fig. 2, and with the cross arm 23 horizontal as indicated by the dot-dash line N, the controller is in its neutral position and the motor 10 is open-circuited. When the rock shaft 22 is oscillated in a clockwise direction (as viewed in Fig. 2) so that the cross arm 23 occupies the angular position indicated by the dot-dash line L, the motor 10 is energized for lowering. Similarly when the rock shaft 22 is oscillated in the opposite or counterclockwise direction, until the cross arm 23 occupies the angular position indicated by the dot-dash line H, the motor is energized for hoisting the usual centering spring (not shown) included in the controller 20, restores the rock shaft 22 to its neutral position when the pull on the cross arm 23 is released.

The contact arrangement for the reversing controller 20 is shown in developed or schematic form in Fig. 3. It includes two rows of fixed contacts 24-26 and 27-29 as well as movable contacts 30-35. The movable contacts are shifted by the rock shaft 22. When the rock shaft is in its neutral position, the center line of the movable contacts occupies the position indicated by the dot-dash line N in Fig. 3, and similarly when the rock shaft is in its hoisting and lowering positions the center line of the set of movable contacts occupies respectively the positions indicated by the dot-dash lines H and L. Single phase alternating current is supplied to the motor 10 through the controller 20 from supply lines L₁ and L₂. In the operation of the device when the controller 20 is shifted to its hoisting position, the main winding 17 of the motor is energized (through a circuit L₁-36-24-31-25-37-17-38-28-35-29-39-L₂) and at the same time the starting winding 18 is energized (through a circuit L₁-36-24-31-40-32-27-41-18-19-42-26-34-43-35-29-39-L₂). Since the speed responsive switch 19 is included in the circuit of the starting winding 18, this winding will be deenergized as soon as the motor comes up to speed and opens the switch 19. Similarly, when the controller 20 is shifted to its lowering position, the motor main winding 17 is energized, although in a reverse sense as compared to that for hoisting (through a circuit L₁-36-24-30-40-31-28-38-17-37-25-33-43-34-29-39-L₂), while the starting winding 18 is energized in the same sense as before (through a circuit L₁-36-24-30-40-31-28-41-18-19-42-26-33-43-34-29-39-L₂). As in the previous case, the speed responsive switch 19 is included in the starting winding circuit and accordingly deenergizes the same after the motor reaches the predetermined speed for which this switch is set.

Before proceeding with the description of the improved actuating mechanism for the controller 20, the parts of the brake mechanism 16 will be identified since the actuating mechanism also serves to operate the brake. The brake mechanism may be of any suitable form and has been shown herein as being of the mechanical type. The particular brake illustrated includes a brake drum 44 fast on shaft 45 of the motor 10 (Fig. 2). This brake drum is embraced by two cooperating brake shoes 46 pivoted on the inner side of the gear case 12 by pins 47. The brake shoes 46 are normally urged into frictional engagement with the brake drum 44 by a pair of helical compression springs 48 surrounding a transverse shaft 49, which is journaled in the housing 14. Cam follower extensions 50, integral with the brake shoes 46, are loosely slideable on this shaft 49 and the springs 48 are interposed between the outer faces of these cam followers and the opposed faces of lugs 51 formed on the housing 14. The cam followers 50 are provided with V-shaped notches in their inner faces which receive a generally diamond-shaped cam 52 that is fixed to the shaft 49 by a pin 53. Consequently, when the shaft 49 is oscillated in either a clockwise or a counterclockwise direction from the position shown in Fig. 2, the cam 52 will push the cam followers 50 apart thereby releasing the brake shoes 46 from the brake drum 44. In general, the actuating mechanism for the motor reversing controller is so arranged that it will cause the brake 16 to be set when the controller 20 is in neutral position and released whenever the con-

troller is moved to either hoisting or lowering position.

In the particular construction illustrated (Figs. 2 and 4), the improved actuating mechanism for the controller 20 and brake 16 embodies a pair of generally horizontal yoke-shaped levers 54 and 55. These levers are pivoted on the inner face of the gear case 12 as indicated at 56 (Fig. 4) and are connected to the opposite ends of the cross arm 23, which is fast on the controller rock shaft or control member 22. This connection to the cross arm 23 is preferably formed by a pair of vertically movable pins 57 and 58 pivoted on the outer ends of the levers 54-55 and having a lost motion connection with the cross arm 23. The pins 57-58 extend through complementary holes in the outer ends of the cross arm and engage the same by means of abutments in the form of nuts 57^a and 58^a threaded thereon. By adjusting the position of the nuts 57^a-58^a on the pins 57-58, the distance can be adjusted through which the levers 54-55 must be moved before a corresponding movement of the cross arm 23 results.

Manual operation of the controller actuating mechanism is accomplished by means of a pair of vertically movable pull cords 59 and 60 (Fig. 1). These pull cords are respectively secured to the lower ends of vertically movable plungers 61 and 62 which are slidably mounted in vertical transverse bores 61^a and 62^a fastened in the outer ends of the levers 54-55 (Fig. 2). Yieldable connections are formed between the plungers 61-62 and their respective levers 54-55 by helical compression springs 63 and 64. These compression springs are interposed between the upper faces of the levers 54-55 and enlarged heads 65 and 66 fashioned on the plungers 61-62.

The actuating levers 54-55 are yieldably retained in their horizontal or neutral positions by cooperating latches 67 and 68 having their outer faces notched at 67^a and 68^a to receive the corresponding levers. The latches are mounted for swinging movement toward and away from the levers 54-55 on pivots 59 and are yieldably urged into engagement with their associated levers by means of a helical compression spring 70 interposed between the adjacent faces of the latches and surrounding lugs 71 and 72 thereon. By arranging the latches 67-68 with the lugs 71-72 thereon in such close proximity, simultaneous release of the latches from their associated levers 54-55 is prevented. This interlocking of the latches makes necessary the sequential movement of the levers 54-55 and introduces a substantial period of time delay between their successive operations.

The latches 67-68 cooperate with the actuator plungers 61-62 and their associated connecting springs 63-64 in such manner that the levers 54-55 and consequently the controller rock shaft 22 are moved with a rapid snap action. To this end, cam surfaces 67^b and 68^b are formed on the outer faces of the latches to cooperate with complementary cam surfaces 65^a and 66^a on the plunger heads 65-66. When the operator pulls down on the cord 59, for lowering of the load hook 11^c, the spring 63 is compressed by the downward movement of the plunger 61 and the latch 67 is finally cammed out of engagement with the lever 54 by the plunger head 65. When the latch disengages the lever 54, the stored up energy in the spring 63 causes the lever to snap downward, thereby quickly shift-

ing the rock shaft 22 in a clockwise direction to its lowering position. Similarly, when the operator pulls down on the control cord 60, the plunger 62 is moved downwardly, compressing the spring 64 until the latch 68 is cammed out of engagement with the lever 55. Upon the disengagement of the lever 55 by its associated latch, it is snapped downward by the compressed spring 64 and thereby shifts the rock shaft 22 in the opposite or counterclockwise direction to its hoisting position.

As was previously noted, the actuating mechanism for the motor controller 20 also serves to control the brake 16. For this purpose, a lever 73 fast on the brake actuator shaft 49 is pivotally connected through an intermediate link 74 with the upright arm 75 of a bell crank lever, which is loosely journaled on the pivot pin 56 of the levers 54-55. The second arm 76 of the bell crank is disposed transversely beneath the levers 54-55. When these levers 54-55 are in their neutral or horizontal position, the bell crank 75-76 is urged in a clockwise direction (as viewed in Fig. 4) by a helical compression spring 77. In such case, the brake actuating linkage occupies the position shown in full lines in Fig. 4 and the brake is set. Upon downward movement of either of the levers 54 or 55, the bell crank 75-76 is oscillated in a counterclockwise direction to the position indicated by dotted lines in Fig. 4 and in which position the shaft 49 is rotated to release the brake 16.

The operation of the hoist illustrated will, in general, be clear from the foregoing description. As a brief résumé, however, it should be noted first of all that when the actuator parts are in the positions illustrated in Figs. 2 and 4, the controller is in its neutral position so that the motor 10 is deenergized, and, furthermore, the brake 16 is set so that if a load is applied to the hook 11^c, there will be no inadvertent descent of the hook due to gravity. If the operator wishes to initiate a hoisting movement of the load hook 11^c, he pulls down on the control cord 60. This causes the controller rock shaft to be moved to its hoisting position with a snap action as was previously described, and at the same time releases the brake 16. Such movement of the controller energizes the motor 10 for hoisting through the circuits noted. The operator keeps the cord 60 pulled down so long as he wishes the hoisting movement to continue. At completion of the desired amount of hoisting movement, he simply releases the cord 60 and the actuator lever 55 is pushed back to its initial or neutral position by the spring 77, which biases the bell crank 75-76. The lever 55 thus releases the cross arm 23 so that the centering spring in the controller 20 is freed to return the controller rock shaft 22 to neutral. Similarly, the operator pulls down on the cord 59 to initiate a lowering movement of the load hook 11^c. Such downward movement of this control cord causes the controller 20 to be snapped to its lowering position and so releases the brake 16. Again, the control cord is held down until the desired amount of lowering movement is completed and then the hoist is stopped by simply releasing the pull cord 59. As before, the spring 77 returns the actuator lever 54 to its initial or neutral position, and the controller rock shaft 22 is freed to return to its neutral position under the action of its associated centering spring so that the motor is deenergized. At the same time the brake 16 is set. It should be noted that in each case when

the actuator lever 54 or 55 is pulled down its associated latch 67 or 68 is swung inwardly so that it prevents simultaneous disengagement of the other latch. As a result, if the operator desires to change over from hoisting to lowering, or vice versa, he is compelled to perform the operation with a relatively long dwell period, during which the brake 16 is set, because of the mutual interference of the latches 67-68. During this period of dwell, the brake 16 quickly decelerates the motor 10 to a point at which the speed responsive switch 19 closes. By virtue of this closure of the speed responsive switch, the motor starting winding 18 is cut into circuit so that the subsequent reversal of the instantaneous polarity of the voltage applied to the motor will cause it to rotate in the opposite direction. The provision of a snap acting type of mechanism also aids in lengthening the period of dwell during which the brake is set, since an appreciable period of time is consumed in storing up the necessary force in the spring 63 or 64 to accomplish the release of their associated levers 54-55. The use of a snap acting type of mechanism has a further advantage in that it prevents either an inadvertent or deliberate attempt on the part of the operator to move the controller 20 slowly to either its hoisting or lowering positions. This latter type of operation is particularly undesirable since it is likely to result in an appreciable interval of time between the release of the load-holding brake and the energization of the motor. If there is any such interval, a load attached to the hook 11c will fall rapidly due to the gravity and thereby quickly accelerate the motor 10 to a dangerous speed. Such acceleration of the motor by a freely falling load is likely to break the centrifugal switch 19 or the motor rotor. Even if the switch 19 is not broken, it is likely to be opened, and with the motor starting winding 18 thereby open circuited, any subsequent energization of the main winding will simply cause the motor to continue rotation in the lowering direction no matter what the setting of the controller contacts may be. Such a snap acting type of actuator, as is herein provided, effectively prevents this dangerous type of operation.

The levers 54 and 55 are preferably arranged not only to form a part of the regular actuating mechanism but also to serve as limit control devices at the respective extremities of movement for the hoisting chain 11a. For this latter purpose, the lever 54 is positioned at one side of the hoisting pinion 11 and within the loop formed in the upper end of the chain 11a, while the lever 55 is positioned on the opposite side of the hoisting pinion and in alignment with an abutment on the lower end of the chain 11a. This abutment has been shown in the form of a collar 78 (Fig. 1) yieldably connected to the chain and hook 11c by a compression spring 79. During the lowering operation, the lever 54 is of course held in its downwardly tilted position. At the extremity of the lowering movement of the chain 11a, the loop in the chain which embraces the lever 54 engages this lever and pulls it back to its horizontal or neutral position, thereby effectively stopping the hoist. Similarly, during the hoisting operation, the other lever 55 is tilted downwardly and at the corresponding extremity of hoisting movement for the chain 11a the abutment 78 engages the lever 55 and swings it upward to its neutral or horizontal position, thereby again stopping the hoist. With this arrangement, an effective limit control is provided for 75

the hoist without the necessity of providing any additional parts. The shock of engagement of the chain 11a with the levers 54-55 is cushioned respectively by the springs 11b and 79. 5 This shock cushioning arrangement is, however, not my invention but is described and claimed in the Whitcomb et al. application noted above.

10 Although a particular embodiment of the invention has been shown and described in some detail, there is no intention to thereby limit the invention to such embodiment, but on the other hand, the appended claims are intended to cover all modifications and alternative constructions within the spirit and scope of the invention.

15 I claim as my invention:

1. An electric hoist comprising, in combination, a revolvable hoist member having a hoisting line reeved thereover for hoisting and lowering movement upon rotation of said hoist member in opposite directions, a single phase alternating current electric motor connected in driving relation with said hoisting member, said motor embodying a main winding and an auxiliary starting winding and being capable of reversal 20 only when said starting winding is energized, means including a speed responsive switch for deenergizing said starting winding when said motor is rotating at a speed in excess of a predetermined value, a reversing controller for said motor embodying a control member oscillatable from a central neutral position in which said motor is deenergized alternatively to hoisting and lowering positions in which said motor is connected to a supply line in respectively reversed 25 senses, means including a brake for releasably holding said motor against rotation, means responsive to the movement of said control member for releasing said brake only when said control member is in its hoisting and lowering positions, means including a pair of actuator members 30 operatively connected to said control member for respectively moving the same to hoisting and lowering position, and time delay means including two latches engageable with said actuator members for delaying the movement of said control member from hoisting position to lowering position or vice versa, whereby said brake is applied during the resultant period of dwell to slow down said motor for actuation of said speed 35 responsive switch.

2. An actuator mechanism for a reversing controller of an electric hoist of the type embodying an electric motor reversible only when its speed is reduced to a predetermined value by an associated brake which is automatically set when the controller is in neutral position and released whenever the controller is shifted to hoisting or lowering position, comprising in combination, a reversing controller member oscillatable from a neutral position alternatively to hoisting and lowering positions, means including a pair of actuator members operatively connected to said controller member for respectively moving the same to hoisting and lowering positions, and means including a pair of separate latches yieldably engaging respective ones of said actuator members for causing said actuator members to move with a rapid snap action upon the application of a predetermined force to said actuator members.

3. An actuator mechanism for a reversing controller of an electric hoist of the type embodying an electric motor reversible only when its speed is reduced to a predetermined value by an associated brake which is automatically set when

the controller is in neutral position and released whenever the controller is shifted to hoisting or lowering position, comprising in combination, a reversing controller member oscillatable from a neutral position alternatively to hoisting and lowering positions, two levers disposed side by side and having the outer ends thereof connected to said controller member on opposite sides of its axis of oscillation, means pivotally supporting said levers at the inner ends thereof for swinging movement in parallel planes on opposite sides of said axis, a pair of latches disposed back to back between said levers, means yieldably urging said latches into engagement with the respective levers, means for moving said latches out of engagement with their associated levers upon the application of a predetermined force to said levers, and means including engageable parts on said latches for preventing simultaneous disengagement thereof from their associated levers.

4. An actuator mechanism for a reversing controller of an electric hoist of the type embodying an electric motor reversible only when its speed is reduced to a predetermined value by an associated brake which is automatically set when the controller is in neutral position and released whenever the controller is shifted to hoisting or lowering position, comprising in combination, a reversing controller member oscillatable from a neutral position alternatively to hoisting and lowering positions, two levers disposed side by side and having the outer ends thereof connected to said controller member on opposite sides of its axis of oscillation, means pivotally supporting said levers at the inner ends thereof for movement in parallel planes on opposite sides of said axis, each of said levers having a transverse aperture therein adjacent its outer end and lying in the plane of movement of the respective lever, a plunger slidable in each of said apertures, each of said plungers having an enlarged head thereon, a helical compression spring surrounding each of said plungers and interposed between the head thereon and the associated lever to form a yieldable resilient connection therebetween, separate pivoted latches disposed back to back between said levers, means yieldably urging said latches into engagement with the respective levers, and means including cooperating cam surfaces on said latches and plunger heads for alternatively moving said latches out of engagement with their respective levers in response to predetermined movement of the associated plunger toward its corresponding lever.

5. An actuator mechanism for a reversing controller of an electric hoist of the type embodying an electric motor reversible only when its speed is reduced to a predetermined value by an associated brake which is automatically set when the controller is in neutral position and released whenever the controller is shifted to hoisting or lowering position, comprising in combination, a reversing controller member oscillatable from a neutral position alternatively to hoisting and lowering positions, means including a pair of actuator members operatively connected to said controller for respectively moving the same to hoisting and to lowering positions, means including a pair of latches yieldably engaging respective ones of said actuator members for releasably holding the same against movement, and means for preventing simultaneous disengagement of said latches.

6. An actuator mechanism for a reversing controller of an electric hoist of the type embodying

an electric motor reversible only when its speed is reduced to a predetermined value by an associated brake which is automatically set when the controller is in neutral position and released

5 whenever the controller is shifted to hoisting or lowering position, comprising in combination, a reversing controller member oscillatable from a neutral position alternatively to hoisting and lowering positions, means including a pair of actuator members operatively connected to said controller for respectively moving the same to hoisting and to lowering positions, and means operably connected with said actuator members for causing a time delay interval between sequential actuations of said actuator members, the last mentioned means including a plurality of elements interconnecting said members and interlocked with each other to compel sequential movement of such elements between sequential 10 actuations of said members and thereby introduce 15 said period of time delay.

7. An actuator mechanism for a reversing controller of an electric hoist of the type embodying an electric motor reversible only when its speed is reduced to a predetermined value by an associated brake which is automatically set when the controller is in neutral position and released whenever the controller is shifted to hoisting or lowering position, comprising in combination, 20 a reversing controller member oscillatable from a neutral position alternatively to hoisting and lowering positions, means including a pair of actuator members operatively connected to said controller for respectively moving the same to hoisting and lowering positions, and means operatively connected with said actuator members and operable in response only to the application to said members of a force exceeding a predetermined value for causing said actuator members to move with a rapid snap action.

8. An electric hoist comprising, in combination, a hoist unit including a revolvable hoisting member and an electric driving motor connected thereto, a hoist line reeved over said hoisting member, means securing one end of said hoist line to said unit with a loop depending between said one end and said hoisting member, load supporting means secured to the other end of said hoist line, an abutment on said hoist line adjacent said last named means, a reversing controller for said motor mounted on said hoist unit and including a control member oscillatable from a central neutral position alternatively to hoisting and lowering positions, a pair of structurally 45 separate generally horizontal levers pivoted for individual movement on said hoist unit on opposite sides of said hoisting member and each having a lost motion connection with said control member on opposite sides of the axis of the oscillation thereof, and manually operable means attached to said pivoted levers for alternatively swinging one or the other of the same downward from its horizontal position to oscillate said control member from its neutral position to its corresponding hoisting or lowering position, one of 50 said levers being disposed within said hoist line loop for engagement thereby at the extremity of lowering movement of said hoisting line and the other of said levers being disposed for engagement by said abutment at the extremity of hoisting movement of said hoist line.

9. An electric hoist comprising, in combination, a hoist unit including a revolvable hoisting member and an electric driving motor connected thereto, a hoist line reeved over said hoisting

member, means securing one end of said hoist line to said unit with a loop depending between said one end and said hoisting member, load supporting means secured to the other end of said hoist line, an abutment on said hoist line adjacent said last named means, a reversing controller for said motor mounted on said hoist unit and including a controller member oscillatable from a central neutral position alternatively to hoisting and lowering positions, a pair of structurally separate control members mounted for generally vertical individual movement on said hoist unit on opposite sides of said hoisting member and each having a lost motion connection with said oscillatable controller member on opposite sides of the axis of the oscillation thereof, and manually operable means cooperating with said vertically movable control members for alternatively shifting one or the other of the same downward from its idle position to oscillate said controller member from its neutral position to its corresponding hoisting or lowering position, one of said control members being disposed within said hoist line loop for engagement thereby at the extremity of lowering movement of said hoisting line and the other of said con-

trol members being disposed for engagement by said abutment at the extremity of hoisting movement of said hoist line.

10. An actuator mechanism for a reversing controller of an electric hoist of the type embodying an electric motor reversible only when its speed is reduced to a predetermined value by an associated brake which is automatically set when the controller is in neutral position and released whenever the controller is shifted to hoisting or lowering position, comprising in combination, a reversing controller rock shaft oscillatable from a neutral position alternatively to hoisting and lowering positions, manually operable actuating means for said rock shaft including a cross arm on the rock shaft and a pair of pull cords operatively connected to respective opposite ends of said cross arm for moving said rock shaft to hoisting and lowering positions, and means including a latch coacting with said actuating means for releasably holding the same against movement to compel the introduction of a period of time delay in the shifting of said rock shaft from hoisting to lowering position or vice versa.

CORNELIUS BRONGERSMA.
